AUTOGRAPHIC REGISTER.

Application filed April 26, 1924. Serial No. 709,106.

This invention relates to an autographic register which has been devised with an object in view of producing a register which contains a form printed record sheet or web, and in which improved means are employed for aligning the superposed form printed sales tickets with the record sheet upon each operation of the register.

A further object is to produce an improved autographic register in which means for preventing the inadvertent withdrawal of the form printed sheets have been provided and in which the register mechanism is automatically locked by the same means, to prevent operation of the register beyond that intended for the issuance of the filled in sales tickets and to secure the proper alignment of the form printed sheets upon the register platen.

A further object is to produce a register in which improved mechanism has been provided for the operation and coordination of the record sheet operating mechanism and the sheet aligning mechanism.

These and other objects are attained in the autographic register described in the following specification and illustrated in the accompanying drawings, in which:

Fig. 1 is a side elevational sectional view of a register embodying our invention, the side having been removed to show the position of the parts of the interior mechanism.

Fig. 2 is a view of a portion of the mechanism disclosed in Fig. 1, showing the parts in different relative positions.

Fig. 3 is a front elevational view of our improved register, the front plate having been removed to disclose the interior mechanism.

Fig. 4 is a fragmental side sectional view of the front end of our improved register, taken on the line 4—4 of Fig. 3 and looking in the direction of the arrows.

Fig. 5 is a view similar to Fig. 4, but showing the parts of the register mechanism in the positions they occupy during certain periods of the register operation.

Fig. 6 is a fragmental side sectional elevation of the front end of our improved register construction, taken on the line 6—6 of Fig. 3 and looking in the direction of the arrows.

Fig. 7 is a plan view of part 87 as shown in Fig. 4.

Fig. 8 is a sectional plan view of a detail 55 of our invention, taken on the line 8—8 of Fig. 13.

Fig. 9 is a view similar to Fig. 8 but showing the parts in different position.

Fig. 10 is a fragmental sectional view of 60 a detail of our invention.

Fig. 11 is a fragmental sectional view of another detail of our invention.

Fig. 12 is a fragmental perspective view 65 of the reel 59 shown in Fig. 1.

Fig. 13 is a somewhat enlarged fragmental perspective view of the front end of a register embodying our invention.

In the register embodying our invention the features to which particular attention 70 will be drawn, are included in three portions of the register mechanism. We will describe these features carefully and separately after the following general description of the register mechanism and construction. 75

The register may be divided for purposes of description of its novel features, into an improved aligning mechanism, an improved record sheet operating mechanism, and an 80 improved mechanism for locking the sheets of the register against inadvertent displacement or withdrawal thereof. These three mechanisms are housed within a suitable casing 13, together with other features of 85 our invention which have been made the subject of a copending application for Letters Patent Serial No. 670,245, filed by us on October 23, 1923, and entitled Autographic register. Within the casing 13 suitable mounting means, such as the rack 14, 15 and 16 upon the sides 17 and 18 of the register, are provided for the spindles 19, 20 and 21 which support the web supply rolls 22, 23 and 24. Above the rolls is the 90 web draw back mechanism 25 which has been shown and described in detail in the application referred to above. We will not enter into a repeated description of this feature of the register construction except to refer generally to the draw back tendency of the rollers 26, 27 and 28 in response to the action of springs 26^a, 27^a and 28^a which are attached to the end of the rollers, together 95

100

100

100

100

with the snubber reaction of the plates or shutters 29, 30 and 31 when the webs are released during the aligning operation as set forth in the copending application.

5 The feeding rollers 32 and 33 are located at the forward end of the register. Roller 32 lies above the platen 34 over which the form printed paper webs pass and is housed by the raised portion 35 of the register cover 10 36 which is hinged upon a pin 37 at the rear of the register as is usual, an opening 38 being provided in the register cover so that the printed form on the paper web may be filled in. The forward end of the cover is 15 locked by hooks 39 as is usual in register construction. The ends of roller 32 have bearing in the upper ends of vertically reciprocal arms 40 and 41 which are held or urged yieldingly in a downward direction 20 by springs 42 and 43 connected to the lower ends of the arms and to the bottom 44 of the register. The shaft 45 of the roller 32 is provided with a pinion 46 which meshes with a gear 47 on the shaft 48 which carries roller 25 33 with which roller 32 cooperates. Shaft 48 is journalled in the sides 17 and 18 of the register casing and terminates beyond side 18 in a crank 49 which is provided with an operating handle 50. Thus when crank 30 49 is operated, the gear 47 will drive pinion 46 and thereby rotate roller 32 together with roller 33.

35 Roller 33 is provided with a notch 51 in its rim so as to free the engagement of roller 32 therewith when the rollers are rotated, as has been set forth in the copending application to which we have referred. In order that there can be no inadvertent withdrawal of the superposed webs or sheets of 40 printed forms, as might occur were the user of the register to pull outwardly upon the projecting ends of the webs during the tearing of the tickets from the web after the feeding rollers are operated to bring the 45 notch of the roller 33 into registration with roller 32 preparatory to the aligning operation, we have provided a device for locking the webs against withdrawal after the aligning operation has been completed. The 50 description of the device for and manner of accomplishing the aligning operation will be reserved for description after completion of the description of the locking device now in hand. Within the crank 49 adjacent to the 55 handle 50 we have provided a plunger 52 which is urged outwardly by a spring 53 which is concealed within the space containing the plunger. This plunger is adapted to engage the outwardly projecting end of a lever 54 which is pivoted at a point 55 inside the register casing and between the ends of the lever, the opposite or inner end of the lever being connected with a spring 56 which retains the lever in its normal position shown 60 in Fig. 13 with the outwardly projecting 65

end of the lever in engagement with the upper end of a slot 57 through which the outwardly projecting end of the lever operates when it is pressed downwardly by the thumb key 58 with which the lever is provided. 70 The position of the crank 49 and its handle 50, as shown in Fig. 8 corresponds to the positions of the attached parts as shown in Fig. 1, and the position of the crank and handle when they are as shown in Fig. 9, 75 corresponds to the positions of the cooperating parts when they are as shown in Fig. 10. When in the positions shown in Figs. 9 and 10 the web locking device we have just described is in web locking position, and when the key 58 is pressed downwardly to release the crank, the register may be operated; all of which operation will be described in detail hereinafter. 80

85 The second of the three features of novelty claimed herein, now will be described as to construction, the description of its operation being reserved until the description of the register construction has been completed. This second feature is the mechanism by 90 means of which the record sheet or web is stored up, filed or rolled within the register casing during its operation and by means of which its printed forms are maintained in continual alignment with the printed forms on the superposed original copy and 95 duplicate copy. Mounted in the extreme forward end of the register casing is a record sheet reel 59. This reel is mounted 100 removably by being mounted in a stationary bearing in side 17 of the casing and in a movable bearing 60 in side 18 of the casing. Bearing 60 is provided with a spring 61, see Fig. 11, which, being located within the bearing cylinder 62 normally holds bearing 60 toward the shaft 63 of the reel 59, a knob 64 on the spindle 65 of bearing 60, permitting the retraction of the bearing against the pressure of spring 61 so that the roll 105 may be removed. A latch 60^a which engages a groove 60^b in bearing 60, locks the bearing in reel-holding position, but is lifted from the groove when it is desired to release the reel. The opposite end of reel 59 is provided with an attached gear 66. This gear meshes 110 with a somewhat larger intermediate gear 67 which is journalled on side 17, and the intermediate gear in turn meshes with a still larger gear 68 which is loosely mounted on shaft 48 of the feed roller 33. In order that gear 68 may be driven upon rotation of crank 49, we have provided a friction drive device which consists of a disc 69 which is splined to shaft 48 and is pressed toward gear 68 by a spring 70, fibre friction discs 71 being located between gear 68 and disc 69 in order that frictional contact between the disc 69 and gear 68 may be sufficient to 115 drive the latter from the former. In order that the paper web which forms the record 120

125 130

sheet, may be attached to the reel 59 so as to wind the sheet thereon as the register is operated, we have provided a groove 72 in the reel, in which the end of the paper strip or web is pressed and held by a presser bar 73 which is pivoted in the ends of the reel. The rate of winding the web upon reel 59 with relation to the rate with which the paper webs are fed from between the rollers 32 and 33, is such that the paper of the lower web or record strip 74 is maintained taut enough to wind it upon reel 59 compactly, the friction discs 71 permitting of slippage between them so that the gear 68 will not 15 rotate as rapidly as does the driving shaft 48 and crank 49. This slipping action takes place to an increasing extent as the accumulation of wound up paper on the reel 59 increases in diameter.

20 We will now describe in detail as to certain features, the means by which the superposed record strip 74, duplicate copy 75 and original copy 76 are aligned periodically so as to bring their printed forms into correct 25 registration with one another. As in all autographic registers the supply of paper used therein is perforated at regular intervals 77, (see Fig. 13) corresponding to the length of the forms which are printed on 30 the webs, such perforations being in the same position relatively to the printed forms, on each of the superposed sheets. In order to secure alignment of these printed forms, the perforations 77 are utilized by causing 35 them to be brought into registration with and then to be forced over or upon the double aligning hooks 78 and 79 secured to a portion 80 of the platen 34 of the register casing. It will be seen that a slot 81 has 40 been provided between platen 34 and its divided portion 80, through which rollers 32 and 33 are permitted to engage and through which the record sheet is passed 45 into the interior of the register casing over a supporting bar 82 and onto reel 59. Therefore, in order to secure alignment of these several superposed webs of paper it is necessary to provide means for aligning the webs, both above and below the portion 80 of the platen, so that the record sheet as well as 50 the duplicate and original copies may be aligned simultaneously. For this purpose we have provided the double alignment hooks 78 and 79 which are located on portion 80 of the platen. Each of these hooks is formed with its hook-like end extending toward the forward end of the register, the rear being shaped to permit the webs or sheets to ride up over them as the register 55 is operated to advance the sheets. As in the register construction disclosed in the copending application to which we have referred above, the draw back rollers 26, 27 and 28 are arranged to impart to the platen 60 supported portions of the superposed webs

a retrograde movement immediately upon the sheets having been released by the notch 51 of roller 33, having been brought into registration with roller 32. The mechanism by which the rollers 26, 27 and 28 are caused 70 to perform this function, will not be described herein, inasmuch as it forms no part of this invention and has been described minutely in the copending application to which reference has been made. However, 75 unless the record sheet is relieved in some manner from the tension under which it is maintained in passing over the record reel 59, as has been previously explained, the platen supported portion of the record sheet 80 can not be retracted so as to align it simultaneously with the superposed duplicate copy and original copy webs. For this purpose we have provided the face of disc 69 with a cam 83 which has one end 84 curved and the other end 85 is provided with an abrupt step-off 86. This cam is adapted to cooperate with a pawl 87 which has a spring 88 adapted to hold it toward and into engagement with either gear 68 or cam 83. 85 For cooperation with the cam the pawl is provided with a finger 89 and for cooperation with the gear it is provided with a detent 90 the latter being shaped to engage the gear between adjacent teeth thereof and 90 the former having its end shaped to ride up and over the curved end 84 so as to rest upon the surface of cam 83 until step-off 86 is reached, at which time a shoulder 91 on the pawl will permit it to drop with its detent 95 between adjacent teeth of gear 68, thereby arresting its movement and causing reel 59 to cease operation by reason of the action of friction discs 71. The operation of this portion of the register mechanism will be described fully in the detailed description of 100 the operation of the register, which will now follow.

Assuming that the person who is to use the register has completed the notations 110 which he desires to make upon the superposed form printed sheets lying upon the platen 34 of the register, his next operation will be to place the thumb of his left hand upon the thumb key 58 of the handle locking lever 54 while at the same time grasping the handle 50. A pressure downwardly upon the key 58 will release the plunger 52 and permit the crank 49 to be rotated. The first rotation of crank 49 will cause roller 33 115 to be rotated from the position shown in Fig. 10 to that shown in Fig. 2. During this initial partial rotation the cam 83 upon disc 69 will have been rotated from the position shown in Fig. 4 to that shown in Fig. 5, 120 the former position corresponding to that of the roller 33 as shown in Fig. 10 and the latter position corresponding to that of the roller as shown in Fig. 2. Two things 125 have happened during this partial rotation. 130

First the rotation of the cam and roller has caused the feeding of the superposed paper webs to be started by bringing the feeding surface of roller 33 into position to press 5 the webs against the surface of upper feeding roller 32 and, secondly, cam 83 has advanced far enough to lift detent 90 from between the teeth of gear 68 by reason of finger 89 having been lifted to ride upon 10 the surface of the cam. Thus, simultaneously with the feeding of the webs, the winding up of the record sheet upon roll 59 has also been started.

Continued rotation of the crank in the direction indicated by the arrow in Fig. 13 will cause gears 66, 67 and 68 to rotate reel 59 much more rapidly than the webs are fed from between rollers 32 and 33, thus taking up any slack which may exist in the record sheet between reel 59 and rollers 32 and 33. This is compensated by the slippage permitted between the friction discs 71. It will be observed that the record sheet passes through an opening 92 in the platen to a position within the register casing and over the inner downwardly projecting aligning hooks 79 which are located in the portion of the platen which extends forwardly of the opening 92. The duplicate copy and original copy strips are passed over the platen and to the outside of the casing after having passed from between rollers 32 and 33 and over the upwardly projecting hooks 78 which are located immediately above and in alignment with hooks 79. In this passage of the respective sheets over the hooks 78 and 79 as above described, the shape of the sheets, when a transverse section is taken of them in a vertical plane through and parallel with the axis of the rollers 32 and 33, is that of a double reverse curvature as they pass over the hooks 78 and 79. This is shown in Fig. 3. This curvature is produced by the compression of the sheets as they pass between the rollers 32 and 33 and are flexed transversely toward their edges in passing over the hooks. Because the record sheet passes beneath the forward portion of the platen in order to be wound upon the record reel 59, we have devised the inverted hooks 79 which will permit of alignment of the record sheet forms simultaneously with the alignment of the duplicate copy and original copy forms. We have found that, were we to draw the record sheet over the upwardly projecting hooks 78 and then downwardly upon the record reel, the ends of the hooks would mar the paper or perhaps tear it. Hence we have provided for the simultaneous flexure of the record web reversely to the duplicate copy and original copy webs. The means whereby the alignment of the superposed printed forms of the sheets or webs is accomplished, is, as we have said above, identical with the means we have pro-

vided in the copending application to which we have referred, and the webs are each provided, as in the construction disclosed in the copending application, with apertures which are regularly spaced in uniformity 70 with the spaced positions of the printed forms on the webs. Thus, as the crank 49 is rotated, the raised portion of roller 33, in cooperation with roller 32, will cause the superposed webs 74, 75 and 76 to be fed from the register until the end of the raised portion of roller 33 is reached. The draw back rollers 26, 27 and 28 will move forward yieldingly to release the sheets from the shutters 29, 30 and 31 so as to allow the 80 webs to be drawn from the supply rolls 22, 23 and 24. This action continues until the sheets are released by the passage of the raised portion of roller 33 from roller 32. Just previous to this the rounded end 84 of cam 83 will have passed beyond the finger 89, thus allowing detent 90 to drop into engagement with the teeth of gear 68. This 85 stops the rotation of feed reel 59 and permits the formation of a slight slackness in record web 74 as the sheets continue to be advanced slightly further until rollers 32 and 33 release them. This slack condition of the record sheet is produced so that retrograde movement of the sheets during the 90 aligning operation will not be hampered. During the formation of the slack in the record sheet the apertures 77 in the superposed sheets will have been brought into engagement with the hooks 78 and 79, and, because 95 the webs have been flexed transversely and held in flexed condition during passage of the sheets over the hooks, the sheets will be permitted to straighten out, with the hooks 100 projecting through the apertures. The instant the roller 33 releases the webs, the draw back rollers 26, 27 and 28 under tension of springs 26^a, 27^a and 28^a will move over the shutters and grip the paper coming 105 from the supply rolls, thereby acting entirely upon the free platen supported portions of the web. These portions will be drawn back quickly and because the hooks 78 and 79 extend through their apertures, the 110 printed forms on the platen supported record sheet, duplicate and original copies will be aligned. The record sheet will have been wound tightly upon the reel 59 and the duplicate and original copies will have been projected beyond the tearing edge of the 115 register cover 36. In the meantime the operator of the register will have rotated handle 49 until its plunger 52 has been fully compressed to bring the crank into engagement with lever 54 as shown in Fig. 8. The 120 position of the roller 33 immediately upon completion of this operation is as shown in Fig. 1, in which the sheets are still free. However, immediately upon release of the handle, the plunger 52 will cause a slight re- 125 130

verse movement of the roller 33 and bring it to the sheet gripping position shown in Fig. 10, because plunger 52 has been forced by spring 53 to move handle 49 backwardly

5 slightly as shown in Fig. 49. This then prevents inadvertent forward movement of the sheets when the duplicate and original copies are grasped and torn off over the tearing edge, thus locking the sheets against 10 placement from aligned position. The register is now in condition for a repetition of the operation above described.

When it is necessary to review or check up the items which have been recorded upon 15 the record sheet, it is but necessary to open the hinged front of the register casing and to pull outwardly upon knob 64 to remove bearing 60 from the spindle 63 of reel 59, the reel thus being freed from support so that 20 it may be taken from the casing. The web 74 is torn off close to the reel. Then the roll of paper is removed from the reel by grasping it and rotating the reel in the direction opposite to the arrow in Fig. 12. 25 This causes bar 73 to free the paper loop from groove 72 of the reel and permit the reel to be slipped from the rolled up paper. The end of the paper web of the record sheet 30 of the register is now slipped beneath the bar 73 as shown in Fig. 12, and, after a few laps of paper are wound upon the reel, it is replaced within the casing and mounted upon its bearings with the gear 66 thereof meshing with the gear 67. Thus the register 35 is again placed in condition for further operation.

Having thus described our invention what we claim is:

1. In an autographic register for use with 40 perforated webs, having a platen, and a web feeding mechanism for drawing the webs over the platen, a registering device projecting above and below the platen, certain of the perforated webs passing above and 45 having their perforations registered with the upwardly projecting portion of the registering device, and certain of the perforated webs passing beneath and having their perforations registered with the downwardly 50 projecting portion of the registering device, both of said upwardly and downwardly projecting portions of the registering device being adapted to enter the web perforations, 55 said feeding mechanism imparting a flexure to the web in an upward direction in passing over the upwardly projecting portion of the registering device, and in a downward direction in passing over the downwardly projecting portion of the registering device during the operation of the feeding mechanism, whereby 60 springlike action of the web is created so that the perforations will be brought into engagement with the registering device immediately upon the perfora-

tions having been brought into registration therewith.

2. In an autographic register for use with perforated webs, having a platen, a web feeding mechanism for drawing the webs over the platen, and a web tensioning mechanism imparting to the webs a tendency to resist feeding movement of the feeding mechanism and to draw the webs in a direction contrary to the direction of web feed when the feeding mechanism is released, a 70 registering device projecting above and below the platen, certain of the perforated webs passing above and having their perforations registered with the upwardly projecting portion of the registering device, and 75 certain of the perforated webs passing beneath and having their perforations registered with the downwardly projecting portion of the registering device, both of said upwardly and downwardly projecting portions of the registering device being adapted to enter the web perforations, 80 said feeding mechanism imparting flexure to the web in an upward direction in passing over the upwardly projecting portion of the registering device and in a downward direction in passing over the downwardly projecting portion 85 of the registering device during the operation of the feeding mechanism, whereby springlike action of the web is created to 90 bring its perforations over the registering device when the feeding mechanism releases the web.

3. In an autographic register having a platen adapted to receive a series of perforated webs, and cooperating rollers adapted to feed the webs a predetermined amount relatively to the platen, said rollers having web contacting surfaces passing out of engagement with each other after the webs 100 have been fed a predetermined amount, stationary aligning hooks projecting above and below the platen, certain of said webs passing above the hooks and one of said webs passing beneath the hooks, said feed 105 rollers imparting an upward flexure to the web passing over the hooks and a downward flexure to the web passing beneath the hooks, whereby the perforations of the webs will be engaged with the hooks upon resumption 110 of the webs to normal flattened condition.

4. In an autographic register having a platen adapted to receive a series of perforated webs, cooperating rollers for feeding the webs a predetermined amount relatively 120 to the platen, said rollers having web contacting surfaces passing out of engagement with each other after the webs have been fed a predetermined amount, and means adapted to impart retrograde movement to 125 the webs after passage of the web contacting surfaces from engagement with the webs, stationary aligning hooks projecting above

5 and below the platen, certain of the webs passing above the hooks and certain of the webs passing beneath the hooks, one of said feed rollers imparting an upward flexure to
 10 the web passing over the hooks and a downward flexure to the web passing beneath the hooks, whereby the perforations of the webs will be engaged with the hooks upon resumption of the webs to normal flattened condition and during retrograde movement thereof.

15 5. In an autographic register for use with a series of perforated webs, having a feeding means comprising a mutilated drive roller and a cooperating pressure roller, the mutilated portion of the drive roller being adapted to relax the pressure of the pressure roller, and a web tensioning device consisting of spring retracted rollers adapted to
 20 effect a retrograde motion of the webs, a double ended web aligning hook adapted to receive the web perforations of certain of the webs over one end of the hook responsive to action of the tensioning device which simultaneously therewith will place the web perforations of the remaining webs over the opposite end of the hook substantially simultaneously with pressure relaxation of the feeding means.

25 6. In an autographic register, having pair of feeding rollers held toward each other for feeding a series of superposed perforated webs between them, said rollers having means adapted to create a spaced position thereof relatively to one another, and means consisting of spring retracted rollers adapted to create a retrograde movement of the webs substantially simultaneously with the occurrence of the spaced position of the rollers
 30 relatively stationary double ended aligning hooks adjacent to the rollers, adapted to create a condition of flexure of certain of the webs in one direction and of others of the webs in an opposite direction during feeding movement thereof between perforations therein, whereby engagement of the perforations with the ends of the aligning hooks will permit the webs to straighten out upon the hooks, said roller spacing means being
 35 arranged for relaxing the webs substantially simultaneously with engagement of the web perforations with the ends of the aligning hooks, action of said means for creating retrograde movement being substantially simultaneous with the occurrence of the engagement of the perforations with the ends of the hooks.

40 7. In an autographic register for use with perforated webs, having a feeding means comprising a mutilated drive roller and a cooperating pressure roller, the mutilated portion of the drive roller being adapted to relax the pressure of the pressure roller, and web retracting means consisting of spring retracted rollers, a double ended web aligning

hook, said web retracting means being adapted to effect the placing of the perforations of certain of the webs over one end of the aligning hook and simultaneously therewith to effect the placing of the perforations of the remaining webs over the opposite end of the web aligning hook substantially simultaneously with the pressure relaxation of the feeding means.

45 8. In an autographic register having a platen for paper webs, means for feeding the webs relatively to the platen, consisting of a pressure roller and a mutilated roller adapted to engage the webs at all times except when the mutilated portion of said roller is brought to register with the webs, and means adapted to effect retrograde movement of the webs substantially simultaneously with registration of the mutilated portion of the mutilated feed roller with the webs, a double ended adjusting hook for adjusting the position of a portion of each of certain of the webs upon one end of the hook and for adjusting the position of a portion of the other webs upon the opposite end of the hook, responsive to action of said retrograde movement means thereon, whereby all the webs will be adjusted relatively to each other and the platen.

50 9. In an autographic register having a platen for paper webs, means for feeding the webs relatively to the platen, comprising a pressure roller and a mutilated roller adapted to engage the webs at all times except when the mutilated portion of said roller is brought to register with the webs, and means adapted to effect a retrograde movement of the webs substantially simultaneously with registration of the mutilated portion of the mutilated feed roller with the webs, a double ended adjusting hook having one end extending above the platen, the opposite end extending below the platen, said first mentioned end of the adjusting hook being arranged to adjust the position of a portion of each of the webs passing in retrograde movement over the upwardly extending end of the adjusting hook responsive to action of said means, the lower end of the adjusting hook being adapted to adjust the position of a portion of each of the webs passing in retrograde movement over the downwardly extending end of the adjusting hook responsive to action of said means, whereby all the webs will be adjusted relatively to the platen over which they pass.

55 10. In an autographic register having a platen for supporting paper webs, means for feeding the webs relatively to the platen, and means located beneath the platen for storing up the second mentioned web, a double ended adjusting hook for adjusting the position of a portion of certain of the webs relatively to the platen upon one end of the hook and for adjusting the position of a

portion of the remaining of the webs upon the other end of the hook, the first mentioned webs which are adjusted by the first mentioned end of the hook being arranged 5 for passage beyond the register during the operation thereof, and the second mentioned of the webs which are adjusted by the second mentioned end of the hook, being arranged for passage beneath the platen of the 10 registering device to be stored up by said storing means.

11. In an autographic register having a frame, a platen supported by the frame for receiving a series of webs in superposed arrangement and over which the webs are drawn, the webs each having apertures spaced longitudinally and crosswise of the web, and web flexing means adapted to flex the webs during movement thereof from one 20 set of apertures to the next longitudinally spaced set of apertures, stationary hooks in spaced relation laterally of the platen, extending above the platen and extending below the platen and adapted to engage 25 through registering apertures of the web, certain of the webs being arranged to pass over and in engagement with the upwardly extending portions of the hooks and certain others of the webs being arranged to 30 pass over and in engagement with the downwardly extending portion of the hooks, the springlike tendency created by the flexure of the webs pressing them against the hooks and causing them to bring their apertures 35 over the hooks when brought into registration therewith whereby the webs will be aligned and movement thereof stopped.

12. In an autographic register having a frame, a platen supported by the frame for receiving a series of webs in superposed arrangement and over which the webs are drawn, the webs each having apertures spaced longitudinally and crosswise of the web, and web flexing means adapted to flex 40 the webs during movement thereof from one set of apertures to the next longitudinally spaced set of apertures, stationary hooks in spaced relation laterally of the platen, extending partially above the platen and partially below the platen and adapted to engage 45 through registering apertures of the web, the springlike tendency created by the flexure of the webs causing them to bring their apertures over the hooks to align the webs and to stop movement thereof, the webs passing over the upwardly extending portions of the hooks being arranged to be projected beyond the registering frame and the webs passing in relation to the downwardly extending portions of the hooks being arranged for passage from above the platen and into the register frame for storage beneath the platen.

13. In an autographic register having a casing, a platen supported by the casing,

a source of web supply located within the casing, a web feeding mechanism located adjacent to the source of supply for drawing the webs over the platen, a web receiving device located adjacent to the feeding mechanism, and means for operating the receiving device from and simultaneously with the operation of the feeding mechanism, a web registering hook in cooperation with the feeding mechanism and extending above and below the platen, the upwardly extending portion of the hook being arranged for passage of certain of the webs over it and beyond the register and the downwardly extending portion of the detent 70 being arranged for passage of others of the webs over it and into the casing for reception by the receiving device.

14. In an autographic register for use with perforated webs and having a feeding means comprising a mutilated drive roller and a cooperating pressure roller between which the webs are passed as the rollers are rotated, the mutilated portion of the drive roller being adapted to relax the pressure 80 of the pressure roller upon the webs, a web tensioning device adapted to effect a retrograde motion of the webs after relaxation of the pressure roller and a mechanism 85 adapted to create a restricted retrograde motion of the feeding means upon completion of the operation thereof and after retrograde motion of the webs has taken place, whereby the unmutilated portion of the drive roller will be brought into engagement 90 with the pressure roller to lock the webs against inadvertent withdrawal from the register, a web aligning hook to receive the perforations of the webs to place the web perforations over the hook and into 95 taut engagement therewith substantially simultaneously with pressure relaxation of the feeding means.

15. In an autographic register for use with perforated webs, having a feeding 110 means comprising a mutilated drive roller and a cooperating pressure roller between which the webs are passed as the rollers are rotated, the mutilated portion of the drive roller being adapted to release the pressure 115 of the pressure roller upon the webs, a platen adapted to receive the webs, a web tensioning device adapted to effect a retrograde motion of the webs upon relaxation of said feeding means, and a spring operatively connected with the feeding means 120 adapted to create limited retrograde motion of the drive roller to bring the unmutilated web feeding surface thereof into cooperative relation with the pressure roller, whereby the webs between the rollers will be maintained in normal locked condition against inadvertent withdrawal thereof from the register, a double ended web aligning hook extending above and below the platen, the up- 125 130

wardly extending portion of the aligning hook being adapted to receive the apertures of certain of the webs and the downwardly extending portion of the aligning hook being adapted to receive the remaining of the webs, said tensioning device being adapted to place the web perforations over and to draw them taut against the ends of the hook

and upon the platen substantially simultaneously with pressure relaxation of the feeding means.

In testimony whereof we have hereunto affixed our signatures.

HARRY H. KONERMAN.
